BURIAL VAULT

Harry W. Loresch, O'Hara Township, Allegheny
County, Pa.

Application February 10, 1933. Serial No. 656,124

12 Claims. (Cl. 72—7)

Formerly it was the practice to place in a grave a wooden rough box in which the casket was thereafter placed and the lid of the rough box was then put in position and the earth filled in.

5 However such rough boxes quickly decayed, permitting the graves to fall in, and furthermore they were not water-tight—a most important consideration.

In modern practice burial vaults comprising 10 a vault body and a lid for the vault body are usually formed of concrete and to strengthen the body and the lid and to enable them to be made of less thickness, the concrete is usually reinforced by means of embedded metal, and when 15 the lid is placed in position it is sealed with interposed plastic material, such as asphalt. However there is still the fault that water will in time get into the interior of the vault, and it is common practice to provide the body of the vault 20 and also the lid with an interior lining of metal.

It is to such interiorly lined vaults that my 25 present invention more particularly relates and my invention is characterized by an improved form of seal between the lid and the body of the vault.

In the accompanying drawing, wherein I have 30 illustrated a practical embodiment of the principles of my invention, Fig. 1 represents a broken longitudinal section of the body and lid of a burial vault, the lid being sealed in position.

Fig. 2 is a cross sectional view of the same taken along the line 2—2 in Fig. 1 and showing the lid elevated slightly.

Fig. 3 is an inverted plan view of the metallic 35 pan which forms the interlining of the lid.

Referring to the drawing, the body of the container is formed of an outer shell 1 of concrete preferably reinforced with embedded metal, such for instance as is described in Letters Patent 40 of the United States No. 1,790,314, issued to me on January 27, 1931. The interior of the body is formed by a metal container 2 having solid walls and bottom and which is secured in place within the concrete body 1 by means of an interposed layer 3 of asphalt or other plastic adhesive 45 material which is also preferably waterproof. At the inside the top of the concrete shell 1 is bevelled to form with the upward extending walls of the container 2 a continuous trough 4, and the plastic material is extended up to fill said 50 trough as shown at 5 in Fig. 2, the top of said material being flush with the top of the metal container 2 and the top of the concrete body 1.

The lid of the vault is formed of a main portion 6 of concrete having its perimetral edge

undercut as at 7 so that when the lid is in place the central or thicker portion of the lid will extend down into the interior of the valve as shown at 8. Secured to the under face of the lid is a metal pan 9 which is fixed to the concrete portion 6 of the lid by an interposed layer 10 of plastic adhesive, such as asphalt. The perimetral edge of the pan 9 is provided with a continuous inverted U-shaped flange 11 for which clearance is provided by the undercut portion 7 of the lid.

12 represents a metal band which is attached to the perimetral edge of the lid and which perimetally encloses the undercut portion 7. The band may be fixed in place relative to the lid by 70 any convenient means. Thus in said Letters Patent No. 1,790,314 the band is shown secured to the metallic reinforcement of the lid. The outer wall of the U-shaped flange 11 preferably does not extend down to the level of the main 75 portion of the pan 9 but the lower end of said outer wall is preferably in the same horizontal plane as is the lower edge of the band 12. The plastic material fills the U-shaped flange 11 and also the undercut portion 7 as shown at 13 in 80 Fig. 2.

When the lid is put in place, as illustrated in Fig. 1, the U-shaped flange 11 fits down over the top edge of the metallic container 2 and the perimetral band 12 fits down over the outer surface of the vault, and the fillings of plastic material 5 and 13 are forced together as illustrated in Fig. 1, thus forming a water-tight and permanent seal between the lid and the body of the container.

The material used for the metal container 2 and the pan 9 may be of any convenient type. Thus a rustproof metal such as stainless steel or iron, copper or the like may be used, but I prefer to use iron or steel having a covering on both 95 sides of vitreous or other enamel which will protect the material from oxidation or other deterioration. The advantage of using enamelled metal is that the same forms a dielectric which prevents electrolysis.

Another advantage in using enamelled metal is that any desired color scheme for the interior of the vault may be provided. If desired the metal may be merely painted.

I claim:—

1. In a burial vault comprising a vault body and a lid therefor both formed of asphalt or similar material, the combination of a container formed of a suitable stiff waterproof material, such as metal, secured in the vault body, and

100

105

110

whose substantially vertical side and end walls extend to substantially the top of the vault body, a substantially continuous trough being formed between the upper part of the vault body and the walls of the container, and a pan of similar material to that of the container secured to the under side of the lid, the pan being provided with a substantially continuous perimetral inverted U-shaped flange which receives the upper portions of the container walls when the lid is in position on the vault body, the lid being sealed in place by plastic material which fills the trough and the U-shaped flange.

2. In a burial vault comprising a vault body and a lid therefor both formed of asphalt or similar material, the combination of a container formed of a suitable stiff waterproof material, such as metal, secured in the vault body by interposed plastic material such as asphalt, and whose substantially vertical side and end walls extend to substantially the top of the vault body, a substantially continuous trough being formed between the upper part of the vault body and the walls of the container, and a pan of similar material to that of the container secured by interposed plastic material to the under side of the lid, the pan being provided with a substantially continuous perimetral inverted U-shaped flange which receives the upper portions of the container walls when the lid is in position on the vault body, the lid being sealed in place by plastic material which fills the trough and the U-shaped flange.

3. In a burial vault comprising a vault body and a lid therefor both formed of concrete or similar material, the lid being undercut perimetral so as to fit down into the vault body, the combination of a container formed of a suitable stiff waterproof material such as metal secured in the vault body, and whose substantially vertical side and end walls extend to substantially the top of the vault body, a substantially continuous trough being formed between the upper part of the vault body and the walls of the container, and a pan of similar material to that of the container secured to the under side of the lid, the pan being provided with a substantially continuous perimetral inverted U-shaped flange which is disposed in the undercut portion of the lid and which receives the upper portion of the container walls when the lid is in place, and a sealing of plastic material filling the trough and the undercut portion of the lid.

4. In a burial vault comprising a vault body and a lid therefor both formed of concrete or similar material, the lid being undercut perimetral so as to fit down into the vault body, the combination of a container formed of a suitable stiff waterproof material, such as metal secured in the vault body by interposed plastic material such as asphalt, and whose substantially vertical side and end walls extend to substantially the top of the vault body, a substantially continuous trough being formed between the upper part of the vault body and the walls of the container, and a pan of similar material to that of the container secured by interposed plastic material to the under side of the lid, the pan being provided with a substantially continuous perimetral inverted U-shaped flange which is disposed in the undercut portion of the lid and which receives the upper portion of the container walls when the lid is in place, and a sealing of plastic material filling the trough and the undercut portion of the lid.

5. In a burial vault comprising a vault body and

a lid therefor both formed of concrete or similar material, the lid being undercut perimetral so as to fit down into the vault body, the combination of a container formed of a suitable stiff waterproof material, such as metal secured in the vault body, and whose substantially vertical side and end walls extend to substantially the top of the vault body, a substantially continuous trough being formed between the upper part of the vault body and the walls of the container, and a pan of similar material to that of the container secured to the under side of the lid, the pan being provided with a substantially continuous perimetral inverted U-shaped flange which is disposed in the undercut portion of the lid and which receives the upper portion of the container walls when the lid is in place, the undercut portion of the lid and the trough being filled with plastic material to seal the vault when the lid is placed in position.

6. In a burial vault comprising a vault body and a lid therefor both formed of concrete or similar material, the lid being undercut perimetral so as to fit down into the vault body, the combination of a container formed of a suitable stiff waterproof material, such as metal secured in the vault body by interposed plastic material such as asphalt, and whose substantially vertical side and end walls extend to substantially the top of the vault body, a substantially continuous trough being formed between the upper part of the vault body and the walls of the container, and a pan of similar material to that of the container secured by interposed plastic material to the under side of the lid, the pan being provided with a substantially continuous perimetral inverted U-shaped flange which is disposed in the undercut portion of the lid and which receives the upper portion of the container walls when the lid is in place, the undercut portion of the lid and the trough being filled with plastic material to seal the vault when the lid is placed in position.

7. In a burial vault comprising a vault body and a lid therefor both formed of concrete or similar material, the lid being undercut perimetral to fit down into the vault body and the undercut portion being surrounded and laterally inclosed by a depending lip, the combination of a container formed of a suitable stiff waterproof material, such as metal secured in the vault body, and whose substantially vertical side and end walls extend to substantially the top of the vault body, a substantially continuous trough being formed between the upper part of the vault body and the walls of the container, and a pan of similar material to that of the container secured to the under side of the lid, the pan being provided with a substantially continuous perimetral inverted U-shaped flange which is disposed in the undercut portion of the lid and which receives the upper portion of the container walls when the lid is in position on the vault body, the trough and the undercut portion of the lid being filled with plastic material which seals the lid to the vault body when placed in position.

8. In a burial vault comprising a vault body and a lid therefor both formed of concrete or similar material, the lid being undercut perimetral to fit down into the vault body and the undercut portion being surrounded and laterally inclosed by a depending lip, the combination of a container formed of a suitable stiff waterproof material, such as metal secured in the vault body by interposed plastic material such as asphalt, and whose substantially vertical side and end walls extend to substantially the top of the vault body, a sub-

stantially continuous trough being formed between the upper part of the vault body and the walls of the container, and a pan of similar material to that of the container secured by interposed plastic material to the under side of the lid, the pan being provided with a substantially continuous perimetral inverted U-shaped flange which is disposed in the undercut portion of the lid and which receives the upper portion of the container walls when the lid is in position on the vault body, the trough and the undercut portion of the lid being filled with plastic material which seals the lid to the vault body when placed in position.

9. In a burial vault comprising a vault body and a lid therefor both formed of concrete or similar material, the lid being under cut perimetral to fit down into the vault body and the undercut portion being surrounded and laterally inclosed by a depending lip, the combination of a container formed of a suitable stiff waterproof material, such as metal, secured in the vault body, and whose substantially vertical side and end walls extend to substantially the top of the vault body, a substantially continuous trough being formed between the upper part of the vault body and the walls of the container, and a pan of similar material to that of the container secured to the underside of the lid, the pan being provided with a substantially continuous perimetral inverted U-shaped flange which is disposed in the undercut portion of the lid and which receives the upper portion of the container walls when the lid is in position on the vault body, the lid being sealed to the vault body by plastic material which fills the under portion of the lid, the trough and the U-shaped flange.

10. In a burial vault comprising a vault body and a lid therefor both formed of concrete or similar material, the lid being under cut perimetral to fit down into the vault body and the undercut portion being surrounded and laterally inclosed by a depending lip, the combination of a container formed of a suitable stiff waterproof material, such as metal, secured in the vault body by interposed plastic material such as asphalt, and whose substantially vertical side and end walls extend to substantially the top of the vault body, a substantially continuous trough being formed between the upper part of the vault body and the walls of the container, and a pan of similar material to that of the container secured by interposed plastic material to the underside of the lid, the pan being provided with a substantially continuous perimetral inverted U-shaped flange which is disposed in the undercut portion of the lid and which receives the upper

portion of the container walls when the lid is in position on the vault body, the lid being sealed to the vault body by plastic material which fills the under portion of the lid, the trough and the U-shaped flange.

11. In a burial vault comprising a vault body and a lid both formed of concrete or similar material, the lid being undercut perimetral so that its center portion will depend within the body with lateral clearance between said center portion and the body, the combination of a container formed of a suitable stiff waterproof material such as metal mounted within the body, the vertical side and end walls of said container extending up to the top of the body and the side and end walls of the body being bevelled at the inside to form with the walls of the container a continuous trough, a pan of similar material to that of the container secured to the under side of the lid, said pan being formed to conform to the depending center portion of the lid and to extend up into the undercut perimetral portion of the lid, the perimetral edges of the pan being formed into a continuous inverted U-shaped flange which hooks downwardly over the exposed top of the container when the lid is in its closing position, and plastic sealing material filling the undercut portion of the lid and also filling said trough whereby the lid is sealed to the body.

12. In a burial vault comprising a vault body and a lid both formed of concrete or similar material, the lid being undercut perimetral so that its center portion will depend within the body with lateral clearance between said center portion and the body and the outer perimetral edge of the lid being provided with a depending flange which receives the upper end of the body, the combination of a container formed of a suitable stiff waterproof material such as metal mounted within the body, the vertical side and end walls of said container extending up to the top of the body and the side and end walls of the body being bevelled at the inside to form with the walls of the container a continuous trough, a pan of similar material to that of the container secured to the under side of the lid, said pan being formed to conform to the depending center portion of the lid and to extend up into the undercut perimetral portion of the lid, the perimetral edges of the pan being formed into a continuous inverted U-shaped flange which hooks downwardly over the exposed top of the container when the lid is in its closing position, and plastic sealing material filling the undercut portion of the lid and also filling said trough whereby the lid is sealed to the body.
